(57) **CLAIM**

The ornamental design for a steering column shroud assembly as shown and described.

DESCRIPTION

FIG. 1 is a front left perspective view of a steering column shroud assembly according to the new design.

FIG. 2 is a front view thereof.

FIG. 3 is a right-side view thereof.

FIG. 4 is a left-side view thereof.

FIG. 5 is a top view thereof.

FIG. 6 is a bottom view thereof; and,

FIG. 7 is a front left perspective view thereof showing the steering column shroud assembly in an installed configuration.

The portions of the steering column shroud assembly rendered in darker gray tones are claimed. The portions of the steering column shroud assembly rendered in lighter gray tones are unclaimed. Light gray tones on interior surfaces of a vehicle in FIG. 7 depict environmental structure that forms no part of the claimed matter.

1 Claim, 7 Drawing Sheets
